UNITED STATES PATENT OFFICE

2,419,373

APPARATUS FOR VIBRATING METALS
DURING CASTINGJewett F. Schrump, West Newton, Mass., assignor
to Metals & Controls Corporation, Attleboro,
Mass., a corporation of Massachusetts

Application September 10, 1943, Serial No. 501,752

2 Claims. (Cl. 22—57)

1

This invention relates to a method of and apparatus for forming metals and alloys.

Among the several objects of the invention may be noted the provision of a method of and apparatus for molding metals and alloys, in which new internal structure is obtained in the metal; the provision of such a method and apparatus in which a substantial grain refinement may be obtained as a molten metal or alloy solidifies; and the provision of such a method and apparatus which is economical and feasible in the use of equipment and operating power. Other objects will be in part obvious and in part pointed out hereinafter.

The invention accordingly comprises the elements and combinations of elements, steps and sequence of steps, features of construction and manipulation, and arrangements of parts which will be exemplified in the structures and methods hereinafter described, and the scope of the application of which will be indicated in the following claims.

In the accompanying drawings, in which is illustrated one of various possible embodiments of the invention,

Fig. 1 is a diagrammatic perspective view showing suitable apparatus for carrying out my process;

Fig. 2 is a copy of a photomicrograph at 30 diameters of commercial zinc cast with treatment by my process and apparatus; and

Fig. 3 is a copy of a photomicrograph of 30 diameters of commercial zinc cast without treatment by my apparatus and process.

Similar reference characters indicate corresponding parts throughout the several views of the drawings.

I have observed that cast metals may during solidification inhibit the growth of large crystals if the metals during solidification are mechanically vibrated at high frequencies in the range of from nine to sixteen kilocycles per second, preferably nine to eleven kilocycles per second. I have also observed that alloying processes function differently if solidification occurs under

2

such vibration, to the extent that new alloy characteristics are produced. Some alloys are brittle because of the formation of embrittling metal components. By means of the invention, these may be controlled through control of the crystal sizes formed during solidification. Also, compression molded powdered metals may have their structure made more homogeneous by vibrating them at said frequencies during molding.

Heretofore, attempts have been made, in the case of cast metals and alloys, to introduce the high-frequency vibrations in the crucibles in which the metals were melted. Since most practical crucibles are made of ceramic material and such does not conduct vibrations very well, little progress was made on the subject. In any event, vibrating a hot crucible involves complex equipment and large loss of power, and furthermore the frequency in that case is not applied during the solidification process, which is important, as will appear. In the case of powdered metal, high-frequency vibration during compression molding has not even been proposed because these are not subject to any melting operation in the process of solidifying compression.

I have found that the various desired effects are obtained if the high-frequency vibrations are introduced during the molding process, instead of the melting process, and particularly during the time that solidification occurs in the case of liquid metals and alloys, or during final compression in the case of compression molded powdered materials. In addition, I have found that a great saving of power can be effected by vibrating less than the entire mold during the solidification process.

Referring now more particularly to Fig. 1, there is shown at numeral 1 a metal mold consisting of two separable parts 3 and 5 which between them produce the matrix or mold cavity 7. For simplicity this cavity is shown as a cylinder for the purpose of casting a cylindric slug about 1½ inches long and ½ inch in diameter. The cavity is open at its upper end as indicated at numeral 9 for inpouring of metal. The sections 3 and 5 are held together for casting purposes by

clamping means 2 consisting of U-connected side members 11 with claws 12, a cross bar 13 under the claws 12, and a clamp screw 15. By assembling the mold as shown in the drawing and tightening up the screw 15, the mold and parts are held assembled. By loosening the screw 15, the parts 11 and 13 may be separated to allow separation of the matrix-forming elements 3 and 5.

In the bottom of the cylinder 9 and closing 10 its lower end is introduced a solenoid core 18 which has a close enough fit in the cylindric opening 9 to seal against any substantial leakage of metal poured into the matrix 7, but with enough clearance to allow free vibratory movement of the core 18. For example, machining parts 3, 5 and 19 with a clearance of about .008" on the $\frac{1}{2}$ -inch diameter is satisfactory.

The core 18 is mounted in the vibration generating apparatus 21 for imparting longitudinal vibrations to the metal in the mold. Suitable apparatus for this purpose is a magnetostriction oscillator of the type shown for example in the Electrical Engineers Handbook of Pender and McIlwain, third edition, section 7, page 128, Fig. 13. (Volume on Communication-Electronics.)

The vibrations are transmitted to the material in the mold but not substantially to the mold.

The armature rod 19 should exhibit magnetostriction characteristics and thus should be composed of the usual alloys for this purpose of iron, nickel, chromium, etc. For example, an alloy having 8 to 10% chromium, 36 to 38% nickel and the remainder iron with 1% or so of manganese to facilitate forging, has been found suitable (see Pender-McIlwain, *supra*).

Only diagrammatic magneto coils 23 of the magnetostriction oscillator have been shown herein because the remainder of the oscillator circuit is known.

Briefly, the rod 19 is magnetically polarized and clamped at a node. It is then placed in the coils 23 carrying alternating current at the desired frequency. This causes the rod 19 to vibrate longitudinally at the frequency of the alternating current. It is desirable to arrange the mechanical form of the rods so that the desired frequency is the resonant frequency of the rod mechanically, in which case the amplitude of the effect will be large even for very small 50 currents in the coil 23.

Other forms of magnetostriction generators for generation of relatively high frequencies may be found at pages 6-11 of "Ultrasonics," by Berman and Hatfield, 1938 (John Wiley & Sons, New York).

Operation is carried out by mounting the mold 1 on a suitable fixed support with the core 19 in position as shown and the rod 21 in position as shown. Hence the core completes the matrix 60 of the mold. The rod 21 is then vibrated, say at eleven kilocycles (11,000 cycles per second) which vibrates the core 19. Since the core 19 in the bottom of the mold fits closely enough to prevent metal from leaking by, but loosely 65 enough to transmit vibration, the end of the core within the mold is vibrating at the above frequency. This arrangement removes the necessity of vibrating the relatively larger mass of the mold, thereby minimizing the vibrating mass 70 which would otherwise be necessary and which is difficult to obtain from reasonably simple magnetostriction generators.

The molten metal, which has been heated elsewhere, such as in an electric furnace, is poured 75

into the mold 1 in which is the vibrating core 19. The metal is allowed to cool and solidify as the vibrations are transmitted thereto.

After the slug 25 has cooled off, the vibration of rod 21 may be ended, the screw 15 loosened and the clamp removed, whereupon separation of the mold parts 3 and 5 will result in falling out of the slug 25.

Typical results may be noted in connection with the pouring of a slug of zinc as indicated at numeral 25. In Fig. 2 is shown a photomicrograph of a sample of zinc which was poured into the mold 1 and solidified under vibrations of 11,000 kilocycles per second from the rod 21; and in Fig. 3 is shown a photomicrograph from the same sample of zinc when poured into the mold and solidified without vibration. The great improvement in fineness of grain is at once apparent in Fig. 2, as compared to Fig. 3.

By pouring alloys into the mold under high frequencies introduced from rod 21, variations are also obtained in alloying characteristics of alloy components poured therein.

Also, compression molding of powdered metals may be effected by compressing these in a chamber having inserted therein high-frequency vibrating plug. This has the effect of orienting the articles of powdered metal more closely as they are brought into a state of final compression.

It will be seen, in view of this invention, that it is not necessary in order to obtain the benefits of high-frequency vibrations in molding processes to vibrate the whole mold. If it were necessary to vibrate the whole mold, the process would become impractical to carry out in connection with molds of any substantial size. However, by introducing the vibrator into an open part of the mold and transmitting vibrations to the contained material in the mold without vibrating 40 the mold as a whole, the useful effects are obtained without the expenditure of unnecessary amounts of energy and without introducing complexities of structure. The vibrations which bring about the desired orientation in structure are transmitted to the mass of material being molded just as well as by shaking the entire mold at the frequencies desired.

Clearly, it is practical to arrange a mold of any shape so that some part is used as a driver in a manner similar to that described in connection with the vibrating core 19.

The term high-frequency is to be interpreted herein as frequencies within the higher ranges audible to the human ear, for example nine to sixteen kilocycles.

It is to be understood that other means may be used for obtaining the vibrations but the chief advantage of magnetostriction generators lies in the simplicity and cheapness of their construction.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A mold comprising separable matrix elements, means for holding said elements together to form a cavity, said elements being formed to provide a cylindric opening joining the cavity with the exterior, a cylindric plug movably sealed

in said opening to prevent leakage, and means for applying high-frequency vibrations to said plug, the end of the plug being exposed to contact by the material which is formed in the mold.

2. A mold comprising separable matrix elements, means for holding said elements together to form a cavity, said elements being formed to provide an aperture joining the cavity with the exterior, a solenoid core movably sealed in said aperture to prevent leakage from said cavity, and means for applying high frequency vibrations to said solenoid core, the end of said solenoid core being exposed to contact by the material which is formed in the mold.
